UNITED STATES PATENT OFFICE.

BASIL R. CRAMPTON, OF CHICAGO, ILLINOIS.

LATCH.

1,273,583.

Specification of Letters Patent. Patented July 23, 1918.

Application filed November 12, 1917. Serial No. 201,529.

To all whom it may concern:

Be it known that I, BASIL R. CRAMPTON, a citizen of the United States, residing at Chicago, in the county of Cook and State 5 of Illinois, have invented certain new and useful Improvements in Latches, of which the following is a specification.

This invention relates to improvements in latches and more particularly to that type 10 of latch adapted for use upon the side doors of automobiles and other vehicles. One object of the invention is to provide a latch of this type that keeps the door under tension while it is in closed position thus obviating any objectionable rattle of the door. A 15 further object is the provision, in the latch itself, of a safety feature whereby the accidental opening of the door caused by pressure upon the same is obviated. A further 20 object is to provide a latch that is of simple construction, efficient in operation and cheap to manufacture.

With the foregoing and other objects in view the invention consists in the combination 25 and arrangement of parts to be herein-after fully described, pointed out in the appended claims and illustrated in the accompanying drawings which form a part of this specification and in which—

30 Figure 1 is a front view of my improved latch illustrating its application.

Fig. 2 is a view similar to Fig. 1 with the movable parts in altered position.

Fig. 3 is a vertical sectional view through 35 the vehicle door and through the frame-block employed, part of the latter being broken away to afford a better illustration, the latch being shown in side elevation.

Fig. 4 is a view similar to Fig. 3 but with 40 the movable parts in an altered position.

Fig. 5 is a fragmentary view of the door jamb showing, dotted, the keeper and the latch-bolt entering or leaving the same.

Fig. 6 is a similar view but with the latch-bolt locked in engagement with the keeper.

Fig. 7 is a perspective view of the keeper.

Fig. 8 is a fragmentary view of the vehicle and its door, from the inside, illustrating the application of the latch.

50 Like reference characters denote corresponding parts throughout the several views.

My latch comprises a base plate 1 secured to the door frame A which is formed with a leg 2 terminating in a curved lip 3, and 55 with a lateral flange 4 bent at right angles to the plate 1 proper. From the plate 1

a tongue 5 is formed, leaving a perforation 6 in the plate, and bent into parallelism with the flange 4, said flange and tongue being themselves formed with aligned perforations 60 whereby the collars 7, 8 are formed which serve as bearings for the latch-bolt 9 which extends through the block B and beyond the said flange 4 and is formed with a bent extremity 10. The said latch-bolt 9 is carried by and movable with the cam 11 which is contiguous to the tongue 5 and is formed with the rounded nose 12 that normally projects into a slot 13 formed in the plate 1 upon the far side of the tongue 5 with relation to the perforation 6. The said cam 11 is formed, further, with a shoulder 14 adapted, in one position of said cam, to bear against the base plate 1. The said cam 11 is formed with an edge recess 15 to receive a 75 prong of the hand lever to be hereinafter described and is tapered toward one end and there formed with the laterally extending heel 16 which is formed with a notch 17 and which terminates in the finger 18 bent at 80 right angles thereto.

A tension bar 19 extends through a perforation 20 formed in the lip 3 and terminates in a head 21 notched for engagement with the notched portion 17 of the said lug 85 16. An expansion spring 22 encircling the said tension bar abuts the said lip 3 and the bar-head 21 to keep said bar and its connections continually under tension. The perforation 20 in the lip 3 is sufficiently large 90 to permit a rocking or oscillating movement of said tension bar as well as a reciprocating movement of the same. The said bar 19 is capable of an oscillating movement from side to side of a plane which would cut the 95 latch-bolt and the perforation 20. This movement of the said tension bar is synchronous with and caused by movement of the said cam 11 which member is guided in its movement by the said tongue 5 and a lug 100 23 formed upon the said plate 1.

To the said base plate 1, I secure a hand lever 24 upon a fulcrum 25, one end of said lever extending above the plate 1 and extending out through an opening in the door 105 lining 26 and through the escutcheon plate 26^a and carrying the hand grip 27, the opposite end of said lever terminating in prongs 28, 29, the latter prong being disposed at right angles to the lever and adapted for engagement with the said finger 18 and the former prong 28 being adapted for move-

ment in the cam-recess 15 and for engagement with the nose 12 of the cam 11. A lug 30 formed upon the said lever is formed with a notch 31 to receive the head 32 of a 5 plunger 33 which extends through a perforation formed in a U-shaped bearing 34 punched from the base plate 1. An expansion spring 35 encircles the plunger 33 and abuts the said lug 30 and yieldingly retains 10 the said lever in frictional engagement with the said bearing 34 to prevent play or rattle of the lever, said spring 35 also serving to yieldingly retain the prong 29 in the path of movement of the said finger 18. Should 15 pressure from the inside of the vehicle tend to force the door open the heel 16 with the finger 18 and connections would move toward the base plate 1 until said finger would engage the said prong 29 which would arrest 20 this movement and effectually prevent opening of the door. Normally the door is opened by movement of the lever 24 which will move the prong 29 out of the path of movement of the finger 18 at substantially 25 the same time the prong 28 rotates the cam 11. When manual pressure upon the lever is removed the spring 35 will return it to normal position.

The body portion of the vehicle is formed 30 with a flange 36 in a rabbeted portion of which a keeper 37 is secured by the screws 38, the said flange 36 receiving the rabbeted portion 39 of the door frame A. The keeper 37 is identical with that shown in 35 my United States patent on locks, No. 1211549, issued Jan. 9, 1917. When the door of the vehicle is slammed shut the bent end 10 of the bolt 9 strikes the curved wall of the keeper 37 as shown dotted in Fig. 5 and 40 the impact moves said bolt into the position shown in Fig. 6 thus locking the bolt and keeper in engagement. The position of the tension bar 19 and spring 22 at this time are shown in Figs. 1 and 3, the tension bar 45 yieldingly retaining the cam and latch bolt in the position shown. To release the latch-bolt the lever 24 is manually moved into the position shown in Fig. 2 thus moving the latch-bolt back to the position shown dotted in Fig. 5, compressing the spring 22 and moving the tension bar beyond the center line 50 of the latch-bolt and perforation 20 when the tension of said bar will yieldingly retain the movable elements in open position. The 55 latch-bolt is now withdrawn from its keeper as the door is opened.

What is claimed is:—

1. In a latch comprising a keeper having a curved wall, a base plate formed with a 60 lateral flange, a latch-bolt journaled in said flange and formed with a bent termination for engagement with the curved wall of the said keeper, a cam fast upon said latch-bolt and formed with a shoulder for engagement 65 with said base plate, a heel integral with

said cam, a finger integral with said heel, a tension bar movably carried by said base plate and connected to said heel, a hand lever fulcrumed to said base plate for operative engagement with the said cam, a prong 70 formed upon said lever and normally disposed in the path of movement of the said finger, and means connecting said lever and the said base plate whereby said lever is yieldingly retained in a predetermined or 75 normal position.

2. In a latch comprising a keeper having a curved wall, a base plate formed with a lateral flange, a tongue bent from said base plate into parallelism with said flange, a 80 latch-bolt journaled in said tongue and flange and formed with a bent termination for engagement with the curved wall of the said keeper, a cam fast upon said latch-bolt and formed with a shoulder for engagement 85 with said base plate, guide means for said cam formed upon said base plate and spaced away from the said tongue, a heel integral with said cam, a finger integral with said heel, a tension bar movably carried by said base plate and operatively connected to said heel, a hand lever fulcrumed to said base plate for operative engagement with said cam, means connecting said lever and the 90 said base plate whereby said lever is yieldingly retained in a predetermined or normal position, and a prong formed upon said lever and disposed in the path of movement of said finger while said cam is in engagement with said base plate and during the 95 normal position of the latter member.

3. In a latch comprising a keeper having a curved wall, a base plate formed with a lateral flange, a tongue bent from said base plate into parallelism with said flange, a 100 latch-bolt journaled in said tongue and flange and formed with a bent termination for engagement with the curved wall of the said keeper, a cam fast upon said latch-bolt capable of engagement with the said base 105 plate, tensioning means for said cam connecting the same and the said base plate, a hand lever fulcrumed to said base plate for engagement with said cam, means connecting said base plate and the said hand lever 110 whereby the latter is yieldingly retained in normal position out of engagement with said cam, and means carried by said lever and cam whereby independent movement of said cam, in one position of the same, with 115 respect to said lever is limited.

4. In a latch comprising a keeper having a curved wall, a perforated base plate formed with a lateral flange, a tongue bent from said base plate into parallelism with 125 said flange, a latch-bolt movably disposed in said tongue and flange and formed with a bent termination for engagement with the curved wall of the said keeper, a cam fast upon said latch-bolt and having a nose 130

- adapted to register with one of the perforations in said base plate and a shoulder adapted for engagement with the said base plate, a heel integral with said cam, a finger integral with said heel, a tension bar connecting said base plate and heel, a lever fulcrumed to said base plate for engagement with said cam, a spring-pressed plunger connecting said base plate and the said 5 plunger whereby the latter is yieldingly retained in normal position out of engagement with said cam, and a prong carried by said lever and disposed in the path of movement of said finger while said cam is in engagement with said base plate and while said 10 lever is in normal position.
5. In a latch comprising a keeper having a curved wall, a base plate formed with a lateral flange and with a perforated terminal lip, a tongue bent from said base plate into parallelism with said flange, a latch-bolt movably carried by said tongue and flange and formed with a bent termination 15 for engagement with the curved wall of said keeper, a cam fast upon said latch-bolt and formed with a shoulder for engagement with 20

said base plate, a notched heel carried by said cam, a finger integral with said heel, a spring-pressed bar connecting the notched portion of said heel and the perforated portion of said lip, said spring-pressed bar being capable of oscillating movement from side to side of a line-of-centers connecting said latch-bolt and the perforated portion of said lip, a hand lever fulcrumed to said base plate and adapted for actuating engagement with said cam, means connecting said base plate and said lever for yieldingly retaining the latter member in normal position out of engagement with the said cam, and a prong carried by said lever and disposed in the path of movement of said finger while said cam is in engagement with said base plate and said lever is in normal position.

In testimony that I claim the foregoing as my own I have hereto affixed my signature in the presence of a subscribing witness.

BASIL R. CRAMPTON.
